UNITED STATES PATENT OFFICE.

WILLIAM B. VANDERBILT, OF WASHINGTON, NEW JERSEY.

DRIVING-REIN HOLDER.

SPECIFICATION forming part of Letters Patent No. 620,997, dated March 14, 1899.

Application filed June 13, 1898. Serial No. 683,378. (No model.)

To all whom it may concern:

Be it known that I, WILLIAM B. VANDERBILT, a citizen of the United States, residing at Washington, in the county of Warren and State of New Jersey, have invented a new and useful Driving-Rein Holder, of which the following is a specification.

My invention relates to improvements in rein-holder devices attached to the dashboards of vehicles for holding the driving reins when not in use by the driver.

The objects of my improvement are, first, to provide a means for easily and quickly attaching and detaching the rein-holder device to and from the dashboard; second, to securely hold each rein—right and left—individually of and at a distance from the other, thereby preventing them from becoming crossed, twisted, or otherwise disarranged, while at the same time in convenient position to be released and used by the driver, and, third, to avoid defacement or injury of the dashboard by the attachment, detachment, or contact of the rein-holder. I attain these objects by the rein-holder device illustrated in the accompanying drawings, in which—

Figure 1 is a front view of the rein-holder; Fig. 2, a sectional top view taken at the line F F, Fig. 1; Fig. 3, a back view, and Fig. 4, an end view, of the rein-holder. The drawings throughout are on a scale of about one-fourth actual size.

Similar letters refer to similar parts throughout the several views.

The rein-holder is constructed of metal, a thin strip of felt or other cloth material covering those parts which would otherwise come into contact with the dashboard.

The rein-holder consists of the horizontal piece D, the upright supports C C, terminating at their upper ends in the curved dashboard-grips B B, the rein-grips A A, the rivets G G, and the felt or other cloth material E E.

The grips A A and B B are springs, the closed or natural shapes and positions of which are indicated, respectively, by A A, Fig. 2, and B, Fig. 4. These springs are constructed of steel or other metal suitable for the purpose and are of sufficient strength and

elasticity to properly perform their respective requirements, as hereinafter specified.

The rein-holder is attached to the dashboard of a vehicle in the following manner: The spring dashboard-grips B B are held open 55 apart from the upright supports C C, as indicated by the broken line, Fig. 4, and then forced down over the top part of the dashboard, all parts of the rein-holder, excepting the spring-grips B B, being on the side of the 60 dashboard toward the interior of the vehicle. The spring-grips B B are then released and immediately they press with sufficient force against the dashboard, and in opposition to the other parts of the rein-holder on the other 65 side of the dashboard, to hold the rein-holder firmly and securely attached to and in contact with the dashboard.

It is understood that the upright supports C C may be shaped to conform with the requirements of the dashboard to which the rein-holder is attached.

To detach the rein-holder from the dashboard, the grips B B are held open, so as not to be in contact with the dashboard, and the 75 rein-holder then raised until free.

The driving-reins when not in use are held securely in a manner and position convenient for immediate release and use by the driver by means of the spring rein-grips A A, one at 80 the right for the right-hand rein and one at the left for the left-hand rein. To secure the reins, the opposite sides of each of the spring rein-grips A A are forced apart sufficiently to admit the rein by firmly pressing the rein 85 edgewise between the two sides of the grips. The force exerted by the springs to regain their natural position holds the reins securely. The reins are released by a reversal of the process by which they are secured—that is, 90 by drawing firmly on the reins and forcing them from the grasp of the rein-grips A A.

To the parts of the rein-holder coming in contact with the dashboard—namely, the back parts of the horizontal piece D, and the upright supports C C, and the inside of the springs B B—is attached a thin strip of felt or other cloth material E E, which prevents defacement or injury of the dashboard.

The upright supports C C and the spring 100

rein-grips A A are attached to the horizontal piece D by means of the rivets G G.

Having described my invention, what I claim as new, and desire to secure by Letters

5 Patent, is—

A rein-holder consisting of a removable transverse bar having a spring-clutch at each end thereof, and supports extending from said

ends and terminating in spring-clamps, whereby the holder is readily removed from the dashboard and easily attached thereto by the spring-clamps, as set forth.

WILLIAM B. VANDERBILT.
